COLLAPSIBLE DISPLAY CARTON

August A. Mertz, Richmond Hill, N. Y., assignor
to P. L. Andrews Corporation, Brooklyn, N. Y.,
a corporation of New York

Application February 10, 1938, Serial No. 189,735

3 Claims. (Cl. 206—44)

This invention relates to a novel construction of collapsible carton for holding, and also for displaying if desired, styliform articles, such, for example, as fountain pens and pencils, crayons, and other kinds of slender or elongated articles; and the invention has reference, more particularly, to a carton for such purposes which can be furnished in flat or collapsed condition subject to interfolding of its parts to form an enclosing holding or holding and displaying container for the articles packed therein.

This invention has for an object to provide a novel carton, for the purposes stated, the body of which is formed from an integral sheet or blank of paper or light weight card-board, the parts of said blank being so arranged as to be foldable and interengageable to form bottom, top, sides and end closures of a container, together with an interior mounting or holder section interlocked with the bottom, and provided with means to receive and support the articles desired to be enclosed within the container.

This invention has for another object to provide in connection with the top and sides of the container, formed as above mentioned, transparent portions through which the enclosed articles may be viewed.

Other objects of this invention, not at this time more particularly enumerated, will be understood from the following detailed description of the same.

An illustrative embodiment of this invention is shown in the accompanying drawings, in which:

Fig. 1 is a top plan view of the novel carton according to this invention as set up and closed to enclose and display the contained articles; Fig. 2 is a side elevation thereof; Fig. 3 is a bottom plan view thereof; Fig. 4 is a longitudinal sectional view thereof, taken on line 4—4 in Fig. 1; and Fig. 5 is a transverse sectional view thereof, taken on line 5—5 in Fig. 1.

Fig. 6 is a plan view of a blank from which the novel carton is formed; Fig. 7 is a fragmentary plan view of the blank with the interior mounting or holder section thereof operatively folded in relation to and interlocked with the bottom of the carton; and Fig. 8 is, in part, a sectional view and, in part, an edge elevation viewed toward the left in Fig. 7.

Similar characters of reference are employed in the above described views, to indicate corresponding parts.

Referring to the drawings, and referring more particularly to Fig. 6, the blank from which the

novel carton is produced comprises an inner bottom section 10 of suitable width and length, contiguous to one longitudinal margin of which and joined thereto by a line of bend or score 11 is one longitudinal margin of one side section 12. 5 Contiguous to the other longitudinal margin of said side section 12 and joined thereto by a line of bend or score 13 is one longitudinal margin of a top section 14. Contiguous to the other longitudinal margin of said top section 14 and 10 joined thereto by a line of bend or score 15 is one longitudinal margin of the second side section 16. Contiguous to the other longitudinal margin of said second side section and joined thereto by a line of bend or score 17 is an outer bottom section 18. Contiguous to the opposite ends of said outer bottom section 18 and joined thereto by lines of bend or scores 19 are end closure members 20, the same respectively having at their outer ends tuck-portions 21 which are likewise joined there- 20 to by lines of bend or scores 22. Connected with the ends of the respective side sections 12 and 16 by lines of bend or scores 23 are foldable side tabs 24. Formed in the marginal portions of the free longitudinal side of said outer bottom section 18, and intermediate the ends of the latter, is an indentation or cut-out 25 within the limits of which is disposed a lock-tongue 26 formed integrally with said bottom section 18. The inner bottom section 10 is provided with a suitably located receiving slit 27 for cooperation with said lock-tongue 26 of said outer bottom section 18, in the manner and for the purposes presently to be set forth. Contiguous to the free longitudinal margin of said inner bottom section 10 and joined 25 to a portion of the latter which extends from one end thereof by a line of bend or score 28 is the primary base panel 29 of a mounting or holder section. Joined to the inner end of said primary base panel 29, by a transverse line of bend or 40 score 30, is one of a pair of holder panels 31 and 31' which are joined by an intermediate transverse line of bend or score 32. Joined to the holder panel 31', by a transverse line of bend or score 33, is a secondary base panel 34. Said sec- 45 ondary base panel 34 and holder panels 31 and 31' are separated from the free longitudinal margin of said inner bottom section 10 by an intervening slit 35, so that said parts are relatively movable longitudinally. Integral with and pro- 50 jecting outwardly from the free end of said sec- ondary base panel 34 is a lock-tongue 36. The inner bottom section 10 is provided with a suit- ably located receiving slot 37 for cooperation with said lock-tongue 36, in the manner and for 55

purposes presently to be set forth. Each holder panel 30 and 31 is provided with one or more article receiving openings 38; corresponding openings 38 of one panel are disposed in longitudinal alignment with those of the other panel.

It is in most cases desirable to provide the novel carton with transparent portions through which the enclosed articles may be viewed. To this end the one or more parts of the top section 14 are cut away to provide an opening or openings 39. Preferably these openings 39 are extended, as at 40, partially into the side sections 12 and 16 for a suitable distance. Adhesively secured to the inner surfaces of said top section 14 and side sections 12 and 16 is a covering or panel 41 of transparent cellulosic material which extends over and glazes said openings 39-40.

In setting up the novel carton, from the blank, constructed and formed as above described, the primary base panel 29 and associated parts constituting the mounting or holder section of the carton is inturned relative to and folded over upon the inner surface of the inner base section 10, whereupon the holder panels 30-31 are bent, along the scores 30, 32 and 33 to respectively assume upwardly inclined relation to the flat plane of the primary and secondary base panels 29 and 34 and in converging mutual relation, thus providing an upstanding support for receiving the articles desired to be affixed thereto and then enclosed within the ultimately formed container. In thus arranging the mounting or holder section, the same as a whole is foreshortened in length relative to the length of said inner bottom section 10, whereby the locking-tongue 36 may be thereupon inserted through the receiving slit 37 provided therefor in said inner bottom section 10, thus anchoring the secondary base panel 34 to the latter so as to retain the mounting or holder section in operative form and disposition upon the interior of the ultimate carton bottom (see Figs. 7 and 8 more particularly).

After thus relating the mounting or holder section to the inner bottom section 10, the articles desired to be closed with the carton, such e. g. a fountain pen A and a pencil B shown in dotted outline in Fig. 1, are respectively inserted through aligned openings 38 of the holder panels 31-31', so that the same are supported in a desired affixed relation to the carton and against movement relative to the ultimately formed carton interior and to each other.

After the articles are thus mounted and supported the closing up of the carton is completed. This is done by turning the side section 12, about the score 11, upwardly into right angle relation to the assembled inner bottom section 10 and mounting or holder section, thereupon turning the top section 14, about the score 13, into parallel overlying relation to said assembled inner bottom section 10 and mounting or holder section, whereupon the other side section 16 is turned, about the score 15, downwardly into right angle relation to said top section 14 and inner bottom section 10, and then turning said outer bottom section 18, about the score 17, into contiguous underlying relation to said inner bottom section 10, and thereupon inserting the locking-tongue 26 into the receiving slit 27 of the latter part, thereby fastening all the thus folded and related parts in operative carton forming relation. When the bottom, top and sides of the set up carton are thus produced, the ends of the carton thereby formed may be closed by turn-

ing inwardly the side tabs 24 and then folding the closure members 20 over the carton ends and securing the same in such position by inserting the tuck-portions 21 into the carton interior in a manner well-known in connection with ordinary types of tuck end cartons.

When the side sections 12 and 16 are operatively disposed at right angles to the top section 14, owing to the fact that the glazed openings or openings 39 extend at 40 across the intersections or corners formed between the top section 14 and the respective side sections 12 and 16, thus forming lateral extensions 42 of the viewing openings, a fuller and better visible disclosure of the contained articles is possible, especially when the carton is viewed from a lateral angle.

It will be observed that the novel carton construction hereinabove described involves an initially flat blank including all the essential parts thereof, and consequently, when in initially collapsed form, the carton material or blanks may be stacked so as to occupy a minimum of storage space until desired for use. It will also be appreciated, that, when a carton is desired, the collapsed blank is so devised that it may be quickly and easily manipulated and set up into desired ultimate carton formation and its parts secured in operative set up relation without necessity of utilizing paste or adhesive.

Furthermore, due to the novel form of the mounting or holder section and the relation thereof to the other carton forming sections and elements, not only is such mounting or holder per se adapted to be quickly and easily erected to service position, but the articles to be supported thereby and ultimately enclosed within the formed carton can be conveniently and easily mounted thereon before setting up the carton section and other elements which is of considerable advantage both in assuring unimpeded access to the mounting or holder and in saving time and labor in manipulating the articles when mounting the same in connection therewith.

While I have shown and described the holder panels as furnished with openings to receive styliform articles, it will be understood that various modifications may be made in this respect and in the form of the holder panels 31-31' themselves in order to adapt the same for the reception and support of other kinds and shapes of articles.

It will be understood various other changes could be made in construction herein shown and described, and many apparently widely different embodiments of this invention could be made without departing from the scope thereof as defined by the following claims. It is therefore intended that all matter contained in the above description or shown in the accompanying drawings shall be interpreted as illustrative and not in a limiting sense.

I claim:

1. A carton made from a one piece blank comprising foldably related bottom, top and side sections and end closure elements, a holder section contiguous to a margin of said bottom section and connected therewith so as to be foldable to superimposed relation to the interior face thereof, said holder section being scored to define connected holder panels and for foreshortening to erect said panels to form an article receiving and supporting means upstanding from the plane of said bottom section, said holder section having a lock-tongue projecting from a margin 75

- thereof, and said bottom section having a slit therein to receive said lock-tongue to thereby retain said holder section in foreshortened holder panel erecting condition.
5. A carton made from a one piece blank comprising foldably related bottom, top and side sections and end closure elements, a holder section contiguous to a margin of said bottom section and connected therewith so as to be foldable to superimposed relation to the interior face thereof, said holder section being scored to define connected holder panels and for foreshortening to erect said panels to form an article receiving and supporting means upstanding from the plane 10 of said bottom section, said holder section having a lock-tongue projecting from a margin thereof, said bottom section having a slit therein to receive said lock-tongue to thereby retain said holder section in foreshortened holder panel 15 erecting condition, said top section having an opening therethrough, and transparent cellulosic material affixed to said top section to cover the area of said opening.
10. A carton made from a one piece blank comprising foldably related bottom, top and side sections and end closure elements, a holder section contiguous to the free side margin of said bottom section and hingedly connected therewith along a portion of its line so as to be transversely foldable to superimposed relation to the interior face thereof, said holder section having a longitudinally contractible free end portion having transverse scores to define two adjacent 15 connected holder panels, said free end portion of said holder section being contractible by bending at said transverse scores to thereby erect said panels so as to form a transverse article receiving and supporting means upstanding from the plane of said bottom section, said holder section having a lock-tongue projecting from its free extremity, and said bottom section having a transverse slit therein to receive said lock-tongue to thereby retain said free end portion of said holder section in contracted holder panel erecting condition. 20
